ELECTRIC FUSE

Joseph Robert McBride, Hampton, Ga., assignor to Southern States Equipment Corporation, a corporation of Georgia

Application January 28, 1954, Serial No. 406,767

12 Claims. (Cl. 200—120)

This invention relates to electric fuses and more particularly to a fuse link for electric fuses and cutouts wherein sealing means is used which normally renders the enclosing structure of the fuse link weathertight, which is yieldable in such a way as to cause the associated fuse or cutout to drop out in the usual manner upon separation of the ends of the fusible element even when conditions are such that an arc is not drawn thereby, and which also is effective to relieve the pressure developed within the enclosing structure due to the establishment therein of an arc by the fusible element.

It is well known that the effectiveness of the current interrupting action of an expulsion type fuse is dependent to a great extent upon the establishment of a high pressure region in the vicinity of the arc established by the fusible element and the prompt venting thereof to a region remote from the arc thereby to scavenge the ionized and other products of arcing from the fuse enclosing structure. Furthermore, the advantageous action of boric acid powder as an aid in arc extinguishment is well understood.

In fuses wherein the fusible element comprises two conductors joined by solder, it is possible for an excessive current to heat the conductors to a temperature far in excess of normal without simultaneously raising the temperature of the soldered joint. Thereafter the current may cease to flow due, for example, to the opening of some other protective device such as an electric circuit breaker or the like and the conduction of heat from the conductors to the solder may later cause the solder to melt even after the cessation of the flow of current therethrough. If no current is flowing when the two conductors separate, it is obvious that an arc will not be established. If no arc is established there will be no pressure developed as in expulsion type interrupters. If no pressure is developed the fuse or cutout may remain intact, i. e. in its normal service position instead of performing a dropout operation. Of course, if the device does not drop out there is no visible indication of the fact that the fusible element has been ruptured.

A principal object of this invention is the provision of a fuse link for electric fuses and cutouts wherein novel sealing means is utilized to render the link weathertight and to allow the device to drop out even though no arc is established upon the separation of a pair of conductors which normally are joined by means of a soldered connection.

A further object of this invention is to provide an improved fuse link for electric fuses wherein releasable sealing means is utilized which renders the fuse link enclosing structure weathertight and which is yieldable to permit prompt scavenging of the fuse enclosure upon the establishment of an arc therein.

Another object of the invention is the provision of yieldable sealing and retaining means for the enclosure of an electric circuit interrupter in which granulated material is used as an aid in arc extinguishment.

2

Still another object of the invention is to provide an improved sealing means for the enclosing structure of a fuse link which also acts as venting means for the device in coordination with the rupture of a fusible element disposed within the enclosing structure.

The invention in one form is applied to a fuse link for electric fuses and cutouts in which boric acid powder is disposed within a tube of insulating material, the ends of which are normally closed and in which a fusible element is mounted in proximity to the powder. According to a feature of the invention one end of the tube is closed by means of a viscous paste and a retaining element normally aids in maintaining the paste in its tube sealing relationship. The retaining element may be releasably held in its normal position by means which is interrelated with the fusible element so that the retaining element and in turn the paste are released in coordination with the rupture of the fusible element.

For a better understanding of the invention reference may be had to the following description taken in conjunction with the accompanying drawing in which Figure 1 is a side view of an electric cutout and in which Figure 2 is an enlarged cross-sectional view of a portion of the fuse tube and parts associated therewith which comprises the interrupting element of the cutout shown in Figure 1.

With reference to Figure 1, the numeral 1 designates a metallic arm which at its left-hand extremity is arranged for mounting on a pole crossarm or other suitable supporting structure (not shown), and which at its right-hand extremity is secured to the upper insulator 2 and to the lower insulator 3. Affixed to the upper end of insulator 2 as by the bolt 4 is the terminal bracket 5 which is provided with a longitudinally split bolt 6, the tines of which are disposed within a pair of openings in terminal bracket 5. Bolt 6 constitutes a means for securing a conductor of the associated circuit to the cutout. Bracket 5 at its upper extremity is provided with an opening 7 for receiving a looped portion of the circuit conductor (not shown) which is secured to terminal 5 by bolt 6. Terminal 5 is provided with a downwardly extending portion 8 to which is affixed by suitable means a metallic brush 9 and a contact element 10. As is well understood in the art, brush 9 could be made of a plurality of laminations of conducting material arranged to bias the contact element 10 toward the right. Pivoted mounted at 11 to bracket 5 is the terminal hood 12 which protects the contact elements from the adverse effects of precipitation. Formed within the hood 12 is a latching surface 12A, the purpose of which will be described later.

Affixed to the lower extremity of insulator 3 by the bolt 13 is the lower terminal bracket 14. Formed within bracket 14 is a slot 15 for receiving one tine of a longitudinally split terminal bolt 16 which is for the purpose of affixing a circuit conductor (not shown) to the terminal bracket 14. Terminal bracket 14 is provided with a pair of longitudinally disposed structures 14A between which is mounted by screw 17 a terminal brush 18 to the upper right-hand extremity of which is attached the contact element 19. Each of the horizontally disposed structures 14A is provided with a jaw portion 20 in which is disposed a trunnion 21. Trunnions 21 are formed integrally with terminal element 22 which is pivoted at 23 to the collar 24 which in turn is affixed to fuse tube 25 by means of the screw 26. Terminal element 22 is also provided with a contacting surface 22A which is engageable with the contact element 19.

Mounted within the fuse tube 25 is a fusible element 27 comprising the conducting elements 27 and 28 which are joined together by solder which is schematically represented at 29 in Figure 2. Secured to the lower end of

conducting element 28 by any suitable means is a conductor 30 which in Figure 1 is shown extending out of the lower extremity of the fuse tube 25. Conductor 30 is electrically connected to the terminal element 22 by suitable means such as a clamping screw (not shown).

From the above description it will be understood that terminal element 22 is retained in the position shown in Figure 1 by means of conducting means in the form of the conductor 30 and parts associated therewith. Furthermore, it will be understood that contact brush 18 is constructed so as to bias the contact element 19 into firm contact making engagement with the contacting portion 22A of terminal element 22.

Secured to the upper extremity of the conducting element 27 is a conductor 31 which in Figure 1 is shown secured by means of the clamping screw 32 to the terminal element 33. Terminal element 33 is provided at its left-hand extremity with a contacting portion 33A against which the contact element 10 is biased by means of the brush 9. Terminal element 33 is pivotally mounted by the pin 34 to a metallic link 35 which in turn is connected by pin 36 to the collar 37 mounted by means of the screw 38 to the fuse tube 25. Thus it will be understood that the conductor 31 and parts associated therewith serve to maintain the parts associated with terminal element 33 in the positions represented in Figure 1. The structure just described which forms the upper terminal assembly of the cutout is more fully described and claimed in U. S. Patent No. 2,172,143 granted September 5, 1939, upon an application of George N. Lemmon and assigned to the assignee of this invention.

Upon the occurrence of a fault or overload condition, the fusible element comprising elements 27-29 is ruptured and the terminal element 22 rotates about trunnions 21 in a clockwise direction. This motion of terminal element 22 allows the pivot 23 to move in a clockwise direction about the trunnions 21 thereby to move the fuse tube downwardly. Simultaneously, the contacting portion 33A is released from the latch 12A formed within the sleet hood 12 thereby to allow the fuse tube 25 and the collar 37 together with the parts associated therewith to swing in a clockwise direction about the trunnions 21. Simultaneously, the terminal element 33 is free to disengage the upper end of the fuse tube 25, all as explained more fully in the above-mentioned Patent No. 2,172,143.

The internal construction details of the fuse tube 25 and parts associated therewith can be best seen from Figure 2. Tube 25 is of conventional construction and is provided with an inner lining element 39 formed of fiber or other suitable insulating material.

The fuse link as constructed in accordance with this invention and as shown in Figure 2 comprises a tubular element 40 of insulating material in which the conducting elements 27, 28, and solder connection 29 are disposed. The upper extremity of tubular element 40 is closed by closure element 41 which is securely affixed to the conductor 31 as by crimping or other suitable means and which is also securely affixed within the tubular element 40 by cement or other suitable means as indicated at 42. While I have found it desirable to construct element 41 with a flange 43, it is obvious that this flange is not an essential feature.

It is well-known that certain materials in the presence of an electric arc are capable of emitting gas, steam, or other suitable substances which are of value in effecting the prompt extinguishment of the arc. Such a substance is boric acid powder 44 which is shown in Figure 2 as being disposed within the tubular element 40 and surrounding the fusible element comprising the parts 27-29. Thus when a fault or overload condition develops, the soldered connection 29 melts to establish an arc in close proximity to the boric acid powder 44 thereby

to initiate the rapid emission of arc quenching gas which aids in interrupting the arc in known manner.

As already explained, it is possible for a fault or overload condition to develop which may rapidly increase the temperature of conducting elements 27 and 28 to an excessive value without appreciably increasing the temperature of the soldered joint 29 until an appreciable time later. Should a circuit interrupter such as an electric circuit breaker effect the interruption of current through the fuse link, it is possible for the soldered joint 29 to melt after the cessation of flow of current through the fusible element. Should this occur there would be no arc established within the region of the boric acid powder 44. If no arc is established, no pressure will be established within the tubular element 40. In cutouts using fuse links which are sealed against moisture with a seal which is unyielding, this condition probably would not result in performance of a dropout operation by the cutout and there would be no visible indication that the fuse link had been ruptured.

In order to insure that the dropout operation will occur, yieldable sealing means for one extremity of the fuse link is provided in accordance with this invention. For example, the lower extremity of the tubular element 40 is closed by means of a viscous fluid generally designated by the numeral 45 together with a retaining element in the form of sleeve 46. One suitable material for use as viscous fluid 45 is silicone paste and preferably the retaining sleeve 46 is provided with a flange 47 for engaging the lower extremity of the tubular element 40.

For the purpose of maintaining the retaining element 46 and the paste 45 in their tube closing relationship under normal conditions, means are provided for interrelating sleeve 46 with the fusible element comprising parts 27-29. As is indicated in Figure 2 this means may be in the form of the collar 48 secured by crimping or other means to the conductor 30. Obviously, collar 48 at its upper extremity is in engagement with the lower portion of sleeve 46.

From the description above it will be understood that the viscous fluid 45 and retaining sleeve 46 not only constitute a yieldable weathertight sealing means for the lower extremity of tubular element 40, these parts in addition are particularly well adapted for retaining the boric acid powder 44 in position within the tubular element 40. Thus, if the junction between the closure member 41 and the upper extremity of tubular element 40 is also made weathertight, the fuse link is rendered entirely free of the adverse effects of changing weather conditions, and since the viscous fluid 45 and sleeve 46 are yieldable once the fusible element is melted it is clear that the fuse link allows the cutout to drop out under the action of gravity and the bias of brushes 9 and 18 even though no arc is established by the fusible element so that a visible indication of the fact that the fusible element is melted is always obtained.

Should a fault or overload condition develop, the boric acid powder 44 effects a rapid generation of arc quenching gas so as rapidly to elevate the pressure within tubular element 40 thereby to effect a prompt piston action of the conductor 30 and parts associated therewith and increase the arc length at a high rate, and also to rapidly scavenge the ionized products of arcing from the interior of tubular element 40.

While a particular embodiment of the invention has been shown and described, I do not wish to be limited thereto and intend in the appended claims to cover all changes and modifications as fall within the true spirit and scope of the invention.

What I claim as new and desire to secure by Letters Patent of the United States is:

1. An electric fuse comprising a tubular element of insulating material, a fusible element disposed within said tubular element, a conductor extending out of at

least one end of said tubular element and electrically connected with said fusible element, the outside of said conductor being substantially smaller than the inside of said tube to define a space therebetween and yieldable sealing means including a viscous fluid and a retaining element normally disposed in said space in proximity to said conductor for rendering said one end of said tubular element weathertight, said retaining element being effective normally to aid in holding said fluid within said tube and being releasable in coordination with the rupture of said fusible element.

2. An electric fuse comprising a tubular enclosing structure of insulating material, a fusible element disposed within said tubular structure, a powder in proximity to said fusible element for emitting arc extinguishing fluid in response to the establishment of an arc by said fusible element, and closure means forming a seal for each end of said enclosing structure, the closure means for at least one end of said enclosing structure comprising a viscous fluid to aid in retaining said powder within said structure and arranged to yield so as to relieve the pressure developed within said structure due to the formation of an arc therein.

3. An electric fuse comprising a tubular enclosing structure of insulating material, a fusible element disposed within said tubular structure, a powder in proximity to said fusible element for emitting arc extinguishing fluid in response to the establishment of an arc by said fusible element, and closure means forming a seal for each end of said enclosing structure, the closure means for at least one end of said enclosing structure comprising a retaining element releasably maintained in its tube closing position, and viscous material within said tubular structure, said retaining element being effective normally to aid in maintaining said viscous material within said tubular structure.

4. An electric fuse comprising a tubular enclosing structure of insulating material, a fusible element disposed within said tubular structure, a first conductor connected with said fusible element and extending out of one end of said tubular enclosing structure, means secured to said one end of said enclosing structure and to said first conductor for securing said first conductor in position and for closing said one end of said enclosing structure, a second conductor connected with said fusible element and extending out of the other end of said enclosing structure, said conductors and said fusible element constituting a series circuit through said structure, a viscous fluid in said other end of said enclosing structure, and a retaining sleeve mounted within said other end of said enclosing structure with said second conductor extending therethrough and operably related therewith to aid in holding said viscous fluid within said enclosing structure, said viscous fluid and said retaining sleeve constituting closure means for said other end of said enclosing structure, said closure means being yieldable in response to rupture of said fusible element.

5. An electric fuse comprising a tubular enclosing structure of insulating material, a fusible element disposed within said tubular structure, a first conductor connected with said fusible element and extending out of one end of said tubular enclosing structure, means secured to said one end of said enclosing structure and to said first conductor for securing said first conductor in position and for closing said one end of said enclosing structure, a second conductor connected with said fusible element and extending out of the other end of said enclosing structure, said conductors and said fusible element constituting a series circuit through said structure, a viscous fluid in said other end of said enclosing structure, and a retaining sleeve mounted within said other end of said enclosing structure with said second conductor extending therethrough to aid in holding said viscous fluid within said enclosing structure, said viscous fluid and said retaining sleeve constituting yieldable clo-

sure means for said other end of said enclosing structure, and holding means for securing said retaining sleeve in position within said other end of said enclosing structure, said holding means being releasable in response to rupture of said fusible element.

6. An electric fuse comprising a tubular enclosing structure of insulating material, a fusible element disposed within said tubular structure, a first conductor connected with said fusible element and extending out of one end of said tubular enclosing structure, means secured to said one end of said enclosing structure and to said first conductor for securing said first conductor in position and for closing said one end of said enclosing structure, a second conductor connected with said fusible element and extending out of the other end of said enclosing structure, said conductors and said fusible element constituting a series circuit through said structure, a powder within said structure for emitting an arc extinguishing fluid in response to the establishment of an arc by said fusible element, a viscous fluid in said other end of said enclosing structure, and a retaining sleeve mounted within said other end of said enclosing structure with said second conductor extending therethrough to aid in holding said viscous fluid within said enclosing structure, said viscous fluid and said retaining sleeve constituting yieldable closure means for said other end of said enclosing structure.

7. An electric fuse comprising an insulating tube, an elongated fusible element disposed within said tube, a first conductor connected with one end of said fusible element and extending out of one end of said tube, means for securing said one conductor in position relative to said tube, a second conductor connected with the other end of said fusible element and extending out of the other end of said tube, the outside of said second conductor being appreciably smaller than the inside of said tube to define a space therebetween, viscous fluid means in the space between said second conductor and said tube and comprising yieldable sealing means for said other end of said tube, and means operably related with said fusible element for normally maintaining said fluid within said tube.

8. An electric fuse comprising an insulating tube, an elongated fusible element disposed within said tube, boric acid powder inside said tube and in proximity to said fusible element, means for securing one end of said fusible element in position relative to said tube, means forming an external electrical connection for said one end of said fusible element, a conductor connected with the other end of said fusible element and extending out of the other end of said tube, the outside of said conductor being smaller than the inside of said tube to define a space therebetween, and viscous fluid sealing means in said space for retaining said powder in said tube and for normally rendering said other end of said tube weathertight, said fluid means being yieldable to relieve pressure formed within said tube due to the establishment of an arc therein by said fusible element.

9. An electric fuse comprising an insulating tube, an elongated fusible element disposed within said tube, means for securing one end of said fusible element in position relative to said tube, means forming an external electrical connection for said one end of said fusible element, a conductor connected with the other end of said fusible element and extending out of the other end of said tube, the outside of said conductor being smaller than the inside of said tube to define a space therebetween, silicone paste in said space, said paste being effective to render said other end of said tube weathertight and to relieve pressure formed within said tube due to the establishment of an arc therein by said fusible element, and means operably related with said fusible element for normally maintaining said paste within said tube.

10. An electric fuse comprising an insulating tube, an elongated fusible element disposed within said tube, boric acid powder inside said tube and in proximity to

said fusible element, means for securing one end of said fusible element in position relative to said tube, means forming an external electrical connection for said one end of said fusible element, a conductor connected with the other end of said fusible element and extending out of the other end of said tube, the outside of said conductor being smaller than the inside of said tube to define a space therebetween, and silicone paste in said space for yieldably retaining said powder within said tube and for normally rendering said other end of said tube weathertight.

11. An electric fuse comprising an insulating tube, an elongated fusible element disposed within said tube, means for securing one end of said fusible element in position relative to said tube, means forming an external electrical connection for said one end of said fusible element, a conductor connected with the other end of said fusible element and extending out of the other end of said tube, the outside of said conductor being smaller than the inside of said tube to define a space therebetween, a retaining element disposed in said space and operably related with said conductor, and viscous fluid means in said space, said retaining element normally being effective to aid in holding said viscous fluid means within said space and being releasable in response to 25 rupture of said fusible element.

12. An electric fuse comprising an insulating tube, an elongated fusible element disposed within said tube, boric acid powder inside said tube and in proximity to said fusible element, means for securing one end of said 30 fusible element in position relative to said tube, means

5
10

forming an external electrical connection for said one end of said fusible element, a conductor connected with the other end of said fusible element and extending out of the other end of said tube, the outside of said conductor being smaller than the inside of said tube to define a space therebetween, and silicone paste in said space, said paste being effective normally to render said other end of said tube weathertight and to maintain said powder therein, and a retaining sleeve releasably maintained within said other end of said tube normally to aid in holding said paste within said space, the normal tension applied between said two external connections by associated mounting equipment being effective to eject said retaining sleeve and at least a portion of said paste from within said tube upon melting of said fusible element thereby to establish an exhaust path to atmosphere from within said tube.
